HINGE

John W. Patton, Philadelphia, Pa., and Roger G. Cudini, Birmingham, Mich.; said Patton assignor to American Car and Foundry Company, New York, N. Y., a corporation of New Jersey

Application August 18, 1948, Serial No. 44,884

3 Claims. (Cl. 20—16)

1

This invention relates to hinges of the flush type, particularly those intended for use on railway car end doors.

It is old in the art to provide doors having a rounded pivoting edge concentric with the axis of the hinges so that the space intervening between the pivoting edge of the door and the rabbed or depressed portion of the door jamb when the door is opened will, regardless of the door position, be insufficient to permit the insertion of fingers and consequent injury by rapid closing of the door due to acceleration or deceleration.

An object of this invention is to provide a hinge structure capable of being fastened to the outer surface of such a door and door jamb, yet having no parts thereof projecting outwardly from its surface. This feature is especially desirable, since projecting parts can cause physical injury to persons who may bump into them, and their elimination provides flush or smooth surfaces which are more in keeping with modern design.

The object of this invention is achieved by offsetting the pivotal axis of the hinge a distance from the edge of the door equal to the radius of the rounded edge of the door and recessing the knuckles of the hinge in the door, so that the knuckles project inwardly rather than outwardly from the hinge plate surface.

Other objects and advantages of the invention will appear from the following specification when read in connection with the accompanying drawings, in which:

Figure 1 is a front elevational view of the hinge;

Figure 2 is a fragmentary horizontal sectional view taken through a door and door jamb above the hinge applied thereto with the door shown in closed position.

Figure 3 is a view similar to Figure 2, but taken through the hinge along the line 3—3 of Figure 1, and showing the door in an open position.

Referring now more in detail to the drawings, the reference numeral 1 refers to a door jamb formed with the conventional rabbed or depressed portion 2. A door 3, having a rounded edge 4 seats in rabbed portion 2.

The hinge, generally indicated at 5, pivotally joins door 3 to door jamb 1. Hinge 5 includes a stationary leaf 6 fixed to jamb 1 and a movable leaf 7 fixed to the door 3 the leaves being formed with knuckles 14 and 18, respectively, substantially U-shaped in cross section and offset therefrom, and a pintle 8 passing through said knuckles to pivotally connect leaves 6 and 7.

2

Stationary leaf 6 comprises a plate 9 of substantially rectangular shape, perforated as indicated at 10 to receive fastening screws, and an extension 11 offset inwardly from and parallel to the plate 9. The vertical edge 12 of the offset extension 11 of leaf 6 is provided with spaced projecting portions 13, which are thickened intermediate their length to form the inwardly extending knuckles 14. Knuckles 14 are provided with aligned cylindrical openings 15 to receive pintle 8.

Movable leaf 7 consists essentially of a plate 16 perforated and countersunk as at 17 to receive screws. The vertical edge 18 of leaf 7 is formed with spaced slots, or openings 19. Each portion of edge 18 at either side and intermediate the length of these slots in leaf 7 is thickened to form the knuckles 20 which are provided also with aligned cylindrical openings 21 to receive the pivot pin 8.

In the assembled hinge, the abutting edges of leaves 6 and 7 intermesh with each other, the slotted edge 18 of movable leaf 7 abutting the vertical edge 12 of extension 11. The projecting portions 13 of extension 11 are adapted to fit into the openings 19 of movable leaf 7 with the vertical edges 22 of projecting portions 13 abutting the vertical edges 23 of slots 19 to provide a substantially continuous and unbroken outer surface. In order to permit free relative movement between leaves 6 and 7 the edges 12 of extension 11 of leaf 6 are beveled inwardly, while the abutting edges 18 of movable leaf 7 are beveled outwardly, the edges 22, 23, respectively, of openings 19 and projections 13 being correspondingly beveled. The leaves 6 and 7 are beveled in this manner to close the gap that would otherwise necessarily be left between them while permitting free relative movement, and also to prevent opening movement of the hinge in more than one direction.

The hinge pin 8 passes through the registered aligned cylindrical openings 15 and 21 of knuckles 14 and 18, respectively, and cooperates with said knuckles to form a pivot element joining the movable and stationary leaves of the hinge. Thickened end portions 24 of pintle 8, of relatively greater diameter than pintle 8 abut against the upper and lower horizontal surfaces, respectively, of the upper and lower knuckles 14, to retain pintle 8 in the aligned cylindrical openings 15 and 21.

A vertical U or channel-shaped recess 25 is provided in door 3, to accommodate the aligned knuckles 14 and 18 of leaves 6 and 7. Horizontal

recesses 22 are provided to permit movement of the door with respect to projecting portions 13 of stationary leaf 6. The recesses 22 extend inwardly from the outer surface of door 3 and are shaped to provide a stop portion 23' engageable with projections 13 to limit opening movement of door 3. The upper and lower edges of the recesses 22 are at the same levels as the upper and lower edges of openings 17 of movable leaf 7. The minimum radius of the vertical wall of recesses 22 is equal to the horizontal distance of the free edge of projecting portions 13 from the center of pivot pin 8.

The stationary leaf 6 and movable leaf 7 are respectively secured to jamb 1 and door 3, by screws 24, as indicated in Figures 2 and 3.

A rubber bead 25 is secured vertically in the rabbeted portion 2 of the door jamb, as shown in Figures 2 and 3, and forms a seal between the door 3 and jamb 1 for the dual purpose of reducing vibration of the door and insulating the car interior. Rubber bead 25 abuts the rounded edge 4 of door 3, which, as heretofore indicated, is concentric with the pivoting axis of the door, so that bead 25 is in contact with the rounded edge 4 of the door regardless of the degree to which the door may be opened.

The hinge functions as follows: When the door is closed, as shown in Figure 2, the leaves 6 and 7 provide a continuous, substantially flat, unbroken outer surface, the outwardly beveled slotted vertical edge of leaf 7 abutting the inwardly beveled vertical edge of extension 11, and the outwardly beveled ends of projections 13 abutting the inwardly beveled ends of openings 17. As the door is opened, leaf 6, being secured by screws 24 to the outer face of the door jamb, remains unmoved, whereas leaf 7, being secured to the door 3, will pivot about pin 8 in accordance with the degree of movement of door 3. As leaf 7 pivots about pin 8, the abutting beveled edges of the leaves are separated and projecting portions 13 of the stationary leaf 6 extend into recess 22 of door 3, in which they are free to rotate until door 3 reaches its maximum open position, at which point further movement of the door 3 is prevented by the engagement of stop portions 23' with the projections 13.

The invention may be modified in various respects as will occur to those skilled in the art and the exclusive use of modifications as come within the scope of the appended claims is contemplated.

What is claimed is:

1. In combination with a door having a substantially U-shaped vertical recess formed therein in adjacent one edge and segment-shaped recesses merging with the U-shaped recess, a hinge for connecting the door with a jamb comprising, a pair of leaves secured to the outer faces of the door and jamb and having spaced apart projecting portions intermeshing with each other,

U-shaped vertically aligned knuckles formed on and offset from the unexposed faces of said intermeshing projecting portions, means pivotally connecting said offset aligned knuckles, said offset aligned knuckles being received in said U-shaped vertical recess in the door when the hinge is applied in place and said projecting portions of the hinge leaf secured to the jamb traversing the segment-shaped vertical recesses in the door when the latter is opened, and a stop formed in said segment-shaped recess engageable by said last-named projecting portions of the hinge to limit opening movement of the door.

2. In combination with a door including a substantially U-shaped vertical recess formed therein, a hinge for connecting the door with an adjacent jamb comprising, a pair of leaves secured to the outer faces of the door and jamb and having spaced apart projecting portions intermeshing with each other, substantially U-shaped vertically aligned knuckles formed on and offset inwardly from the unexposed faces of said intermeshing projecting hinge leaf portions and adapted to fit into the U-shaped vertical recess in the door when the hinge is applied in operative position, and means pivotally connecting said offset aligned knuckles, the exposed faces of said pair of hinge leaves cooperating to form a substantially flat unbroken surface when the door is closed.

3. In combination with a door including a substantially U-shaped vertical recess formed therein, a hinge for connecting the door with an adjacent jamb comprising, a pair of leaves secured to the outer faces of the door and jamb and having spaced apart projecting portions intermeshing with each other, substantially U-shaped vertically aligned knuckles formed on and offset inwardly from the unexposed faces of said intermeshing projecting hinge leaf portions and adapted to fit into the U-shaped vertical recess in the door when the hinge is applied in operative position, and means pivotally connecting said offset aligned knuckles, the abutting vertical edges of said leaves and said spaced apart intermeshing projecting portions being correspondingly beveled to prevent opening movement of the door in more than one direction.
